UNITED STATES PATENT OFFICE.

ROBERT M. FRANCY, OF TORONTO, OHIO.

DESIGN FOR A FIRE-CLAY STOVE-PIPE.

SPECIFICATION forming part of Design No. 15,391, dated September 9, 1884.
Application filed June 9, 1884. Term of patent 7 years.

To all whom it may concern:

Be it known that I, ROBERT M. FRANCY, residing at Toronto, in the county of Jefferson and State of Ohio, have invented and produced 5 a new and original Design for a Fire-Clay Stove-Pipe, of which the following is a specification.

My new design for a fire-clay stove-pipe consists in an octagonal configuration for the body 10 of the stove-pipe in its transverse section, with its several faces or sides presenting elongated upright flat surfaces, and in an enlarged socket for said body, also of octagonal configuration in horizontal section, having its sides of convex 15 form in direction of their depth. Such octagonal configuration applies to the exterior of the stove-pipe, the interior of which may also be of octagonal shape to correspond, or round, as desired.

Reference is had to the accompanying drawing, which forms a part of this specification, and which represents a view in perspective of a stove-pipe with attached socket in accordance with my design.

25 A is the upright body of the stove-pipe, and

B its socket, both of octagonal configuration in horizontal section, but the body part A presenting upright elongated flat sides *a a* throughout the whole of the octagonal frame, while the several sides *b b* of the enlarged portion B are of a graceful convex form in direction of their depth, and so that the angles of their sides are in line with and meet the angles of the sides of the body part A. The several sides *a* and *b*, or any of them, may, 35 if desired, have ornaments on them, or be left plain, as shown.

I claim—

The within-described design for a stove-pipe, which consists in a body part, A, of octagonal configuration in horizontal section, 40 with its side *a a* of upright flat surfaces, and a spread socket part, B, also of octagonal configuration in horizontal section, but with its sides *b b* of convex form in direction of their 45 depth, as shown.

ROBERT M. FRANCY.
